(57) **CLAIM**

The ornamental design for footwear welt portion, as shown and described.

DESCRIPTION

FIG. 1 is a front perspective view of the footwear welt portion embodying the new design;

FIG. 2 is a side view thereof; and,

FIG. 3 is a rear perspective view thereof.

FIGS. 1–3 show features of an article of footwear in phantom lines. These features are shown for environmental purposes and do not form any part of the claimed design. Further, the phantom lines immediately adjacent the solid-line portions of the design form the boundary of the design, with the phantom lines forming no part of the claimed design.
